UNITED STATES PATENT OFFICE.

EARL L. PETERSON, OF CORONA, NEW YORK, ASSIGNOR TO UNITED CONCRETE PIPE COMPANY, OF NEW YORK, N. Y., A CORPORATION OF DELAWARE.

CONCRETE PIPE.

Application filed August 24, 1920. Serial No. 405,702.

To all whom it may concern:

Be it known that I, EARL L. PETERSON, a citizen of the United States of America, residing at Corona, county of Queens, Long Island, and State of New York, have invented certain new and useful Improvements in Concrete Pipe, of which the following is a specification.

My invention relates to concrete pipe, and particularly to the joint between abutting pipe sections. The object of my invention is to provide a simple and practicable expansion joint, the elements of which may be readily fabricated and molded into the pipe ends while at the same time affording improved efficiency in operation. The present construction is in a measure related to that shown in the Scofield Patent 1,346,687, of which it is a development.

In the accompanying drawings—

Fig. 1 is a longitudinal section through portions of abutting pipe ends in which my invention is embodied in one form.

Fig. 2 is a section on the line 2—2 Figure 1.

Fig. 3 is an end elevation of a portion of the spigot pipe.

Fig. 4 is a similar view of the bell pipe end.

Figs. 5 to 15 inclusive, are views similar to Fig. 1, but showing various modified forms of joints.

The joint shown in Figs. 1 to 4 is specially adapted to relatively low pressure conduits. That is to say, conduits through which fluid or gas passes at a pressure not exceeding forty or fifty pounds. As here indicated, the pipe section 20 is provided with a projection spigot flange 21, and two wire mesh cages 22 and 23 respectively, the former terminating adjacent the abutment face 24 at the exterior portion of the joint, while the second mesh 23 projects beyond the terminal face 25 of the spigot flange.

The bell end section 26, which corresponds to the opposite end of the section 20, discloses the position of the meshes 22 and 23 at that end of the section. As indicated, the mesh 22 is embedded in the bell flange 27 adjacent the wall 28 thereof, while the mesh 23 is also embedded in the terminal

face 29 at the inner portion of the joint, and preferably forms the body of the bead 30 projecting beyond the face 29. The faces 55 25 and 29 of the pipe ends are spaced apart when the abutting faces 24 and 28 are engaged in the completed joint position, thus affording a channel 31 at the interior face of the joint, to permit certain joint sealing 60 operations hereinafter referred to, as well as to receive the grout which is trowelled into the channel to finish the seal of the joint, and to afford a smooth flow surface at this point. 65

In order to render the joint gas and fluid tight, regardless of expansion and contraction of the line under varying temperature conditions, I embody in the ends of the pipe sections, a pair of sheet metal rings 32 and 70 33. The ring 32 which is embedded in the spigot pipe end is shaped as a truncated double cone, one portion of which is embedded in the body of the pipe and is provided with any suitable anchorage device, 75 such as apertures 34, while the other portion thereof overlies the spigot flange 21 of the pipe, and rests thereon. At the junction of the two oppositely inclined portions of the ring 32, it is crimped at 35, and a 80 water proof plastic or fibrous packing 36 rests therein. The crimp 35 and consequently the fibrous packing 36, are located at the junction between the spigot flange 31 and the abutment wall 24 of the conduit, 85 so that when the joint is made, the interior edge of the bell flange 27 of the pipe section 26 engages and compresses the packing 36, and thus effectively seals the joint at that point against the entry of moisture 90 from the exterior of the pipe.

The second ring 33 embedded in the spigot pipe end 26 is also of truncated double cone shape, but with the apices, instead of the bases, of the cones facing each 95 other. The embedded portion of the ring is similarly provided with anchoring means, such as perforations 37, while the other portion of the ring forms an interior facing for the bell flange 27. The junction of the 100 two sections is similarly provided with the crimp 38, located at the junction of the bell flange 27 and the end face 29, while a similar packing 39 is arranged in the crimp at this

point. It is thus seen that in the completed joint, the portions of the rings which on the one hand over-lie the spigot flange 21 and face the interior portion of the bell flange 27, over-lap each other and afford the meeting faces of the spigot and bell elements of the joint. After the joint has been assembled, the projecting margin of the ring 32, which lies at the bottom of the channel 31 at the interior face of the joint, is preferably sealed to the exposed portion of ring 33. If the rings 32 and 33 are formed of tin, the seal may be effected by soldering. If they are iron or steel, however, as I prefer, the joint is sealed by welding at 40.

When the joint is subjected to strains incident to contraction of the pipe lengths, crimps 38 and 35 are free to yield without rupturing the seal at 40, by reason of the presence of the flexible packing 39 or 36, which while excluding cement from the area adjacent the crimps leaves the latter free to change contours under the strains to which the pipe is subject. It will be understood, of course, that after the seal 40 has been effected, the channel 31 is filled with grouting. The latter adheres and makes bond with the projecting portion of the mesh 23, at the end of the spigot, while the opposite face of the channel is painted with any suitable preparation which will prevent the bonding of the grout therewith. Consequently when the joint opens, the separation between the grout fill and the spigot end 26, occurs adjacent the face of the channel provided with ribs 30 which afford a long creepage surface, and thus aid in preventing access of the fluid to the seal at 40.

In the modification shown in Fig. 5, the exposed joint faces are substantially the same as those just described. I have indicated, however, reinforcing longitudinal bars 41 and 42 in the spigot end of the pipe, to which ring 32 is connected by welding at 43 and 44, while the meshes 22 and 23 are united by tie wires 45. The bell end is similarly reinforced by longitudinal bars 46 and 47 to which the ring 33 is welded at 48, while the tie wires 45 connect the mesh to these bars. The latter may be also connected to each other by any suitable means such as tie wire 49, as indicated at the left hand end of the figure. This construction has the advantage of rigidly uniting and interconnecting the various metallic elements of the reinforce and joint so that the strains of expansion and contraction are transmitted directly to the joint structure by the metal reinforce instead of through the interposed concrete, as in the construction first described.

In Figure 6, I have shown a modification of the structure particularly adapted for making the seal in a channel at the exterior

instead of the interior of the pipe. To this end the spigot flange 50 of the pipe section 20 is extended sufficiently to abut against the body of the bell end 26, while the bell flange 51 of the latter is shortened. The exterior channel 52 is provided to receive the grout fill. The sealing ring 53 for the spigot end of the pipe is here shown as a plain cylinder and over-lies a similarly shaped portion of the spigot flange 50. The mesh reinforce 22 and 23 is tied to the cylinder in any suitable way, as by welding the inner ends of tie wires 54. The ring 55 of the bell end of the joint has a cylindrical section embedded in the pipe 26 and an outwardly flared conical portion 56 terminating in the crimp 57 and flange 58. The latter over-lies the exposed end of the ring 53 and is welded or otherwise sealed thereto at 59. The flexible packing ring 60 may be arranged with the crimp 57 where it is compressed during the making of the joint. A similar packing ring 61 may be arranged in the channel 62 in the abutting face of the bell end pipe section 26 and is similarly compressed by the face 63 at the end of the spigot flange. The packings 60 and 61 serve to exclude moisture from the inner face of the joint at 59, and by reason of their flexible nature, not only expand to keep the joint tight while the sections separate on contraction, but also permit the functioning of the crimp 57 under the latter condition.

In Figure 7, a further modification is shown in which the bell and spigot flanges 100 are so shaped as to afford sealing channels 64 and 65 at both the exterior and inner portions of the joint. The reinforcing ring 53 for the spigot end of the pipe is identical with that shown in the previous construction, and its exposed portion again over-lies the cylindrical portion of the spigot flange. The reinforcing ring 66 for the bell end is similarly cylindrical, and is embedded in the bell flange 67, emerging from the end of the latter, instead of forming a facing for the bearing surface thereof. In the exposed portion of the ring projecting beyond the bell flange 67, a crimp 68 is formed, while the terminal flange 69 over-lies the end of the ring 53 of the spigot section, and is welded or otherwise sealed thereto at 70. The mesh reinforce 22 for the spigot end is welded at 71 to the ring 53, while the double mesh reinforce 72 extending both inside and outside the ring 66 for the bell end is welded thereto at 73. In order to seal the inner channel 65, a packing ring 74 is positioned at the bottom of the channel before the joint is made, and is compressed by the end of the spigot flange as the pipes are drawn together. The packing ring 75 lying in the crimp 68, excludes the grouting therefrom when the channel 64 is filled, and permits the crimp 130

to function under the strain to which it is subjected under various temperature conditions.

The adaption of this type of joint to a sealing channel at the inner portion of the joint is indicated in Figure 8. Here the ring 76 is embedded in the spigot end 20 of the pipe and projects beyond the end face of the spigot flange 77, which is under-
10 cut and faced by portion of the ring 76. The bell end 26 has embedded therein a ring 78 with marginal crimp 79 adjacent the sealed joint 80, between it and the projecting margin of the ring 77. The bell flange 81 has a terminal groove 82 to receive the packing 83 which is compressed in the completed joint, and prevents moisture from creeping into the seal from the exterior of the pipe. A packing ring 84, located in 20 the crimp 79, permits the latter to function.

In the modification shown in Figure 9, the spigot is provided with a ring 85 of truncated cone shape, which rests upon the outer face of the spigot flange 86 and projects beyond the latter terminating in an inwardly off-set flange 87. The bell end is provided with an embedded ring 88 with a terminal flange 89 off-set to over-lie the end of the pipe at the side of the inner joint channel 90. The marginal crimp 91 extends toward and deflects the flange 87 of the ring 86 when the joint is made, thus bringing the two portions into intimate contact which is supplemented by a welded joint between these flanges. The space 92 permits flexion of the flanges under varying temperature conditions without a tendency to rupture the seal. The packing rings 93 at the 35 abutting surfaces of the bell flange 94 and the body of the spigot end 20 prevents leakage to the joint from the exterior of the pipe, while a second packing ring 95, arranged in the end of the spigot section 40 26 before the grouting is filled in channel 90, tends to maintain the joint tight at the parting face as the joint opens.

The adaptation of this construction to an exterior joint channel is indicated in 50 Figure 10, the corresponding points being similarly identified.

In Figure 11 still another modification is shown. As here indicated, the bell and spigot flanges are faced on their meeting and inclined surfaces by exposed portions of the embedded frusto-conical rings 96 and 97, each provided with a crimp 98 to receive a packing ring 99. Bearing against the crimps and holding the latter firmly 60 in position, are reinforcing bars 100 and 101, which hold the crimps so rigidly in position that when the pipe ends are forced together, a very snug joint between the ends of the crimps 98 and the portions of 65 the rings 97 and 96, against which they

bear, is accomplished. This very materially assists in welding or otherwise mechanically sealing the joint at 102, the channel 103 being then filled with grout. While an inner channel is shown in this figure, it can be 70 readily seen that by increasing the length of the spigot and decreasing the length of the bell, the channel will be formed at the outer portion of the joint, and will uncover the outer crimp 98, while the present 75 channel 103 will be completely closed by the projecting spigot end.

Figure 12 shows a construction substantially identical with that indicated in Figures 1 to 5 inclusive, but showing the 80 doubled coned rings welded or otherwise suitably secured to metal shells 104 embedded in the respective spigot and pipe ends. A welded joint is indicated at 105, but it will be readily understood that where 85 more convenient, the parts may be riveted together or the ring formation may be made integral with the shell ends.

In Figure 13 the same adaptation of the joint shown in Figure 9 to a shell construction is indicated, the ring formation being here disclosed as an integral continuation of the shells 104.

In Figure 14 the rings 106 and 107 have each a double cone shape as in Figure 1, 95 but are provided at their opposite margins with crimps 108. The embedded crimps form an anchorage and are secured to the concrete pipe ends or to the shell or other reinforce, indicated at 109. As here shown, 100 the bell and spigot flange 110 and 111 respectively, are made very short and inner and outer channels 112 and 113 respectively result. This makes it possible to seal the joint both outside and inside at 114. Packing rings 115 arranged in crimps 108 may be provided, but are not necessary although they tend to maintain the joint tight should either of the seals at 114 become defective.

The construction shown in Figure 15 differs from that just shown only in that the over-lapping crimps 116 and 117 of the construction just described, afford a single chamber into which a sealing material, such as lead, can be poured by opening a hole 115 in the rings after the joint has been made, or by packing lead rings therein before the pipe sections are assembled. Should any displacement of the crimps 116 and 117 occur during the assembling of the joint 120 with lead rings in position, the joint may be properly closed before sealing at 118, by suitable calking operations. It will be recognized that in both Figures 14 and 15, the construction may be readily modified 125 to afford a single joint chamber either exterior or interior to the joint.

It will, of course, be understood that whether or not the metal rings be carried the length of the conduit section as in cer- 130

tain of the constructions illustrated, the joint elements function in the same manner, and I contemplate such extension of the rings whenever it is desired to embody a 5 metal shell throughout the length of the pipe. Nor, of course, is it essential that the rings be integral with the shell in such case, since they may be joined together in any appropriate fashion to meet the needs 10 of a particular installation. My claims are to be interpreted accordingly, to include any type of conduit body construction having at the joint cooperating elements embodying the invention specified. In all the 15 constructions it is obvious that the metal ring may be mounted on or associated with the end form of the mold on which the conduit is cast, and that this element of the construction offers no obstacle or impediment 20 to the formation of the conduit in the manner usually practiced in this art. Moreover, it will be recognized that the ring elements are, in all of the various forms shown, readily fabricated either in 25 the shop or in the field by means of simple crimping or bending rolls adapted to operate on sheet metal.

Various other modifications will readily occur to those dealing with the problem, 30 which do not depart from what I claim as my invention.

In the following claims I use the expression "oppositely inclined" to identify the outwardly flared bell end and the inwardly contracted spigot end elements of the joint-forming rings, it being of course understood that the actual inclination of the opposed joint surfaces, with respect to the pipe axis, is substantially the same, and that the 40 outer peripheral surface of the spigot and the inner peripheral surface of the bell lie in juxtaposition in the completed joint.

I claim:

1. A joint for concrete conduit sections 45 comprising bell and spigot ends, and metallic ring elements each of double cone shape respectively anchored in the conduit ends, and having oppositely inclined exposed faces juxtaposed in the finished joint.

50 2. A joint for concrete conduit sections comprising bell and spigot ends, and metallic ring elements each of double cone shape respectively anchored in the conduit ends, and having oppositely inclined exposed portions 55 facing the bell and spigot surfaces of the respective ends.

3. A joint for concrete conduit sections 60 comprising bell and spigot ends, and metallic ring elements respectively anchored in the conduit ends, and having oppositely inclined exposed faces juxtaposed in the finished joint, together with means uniting 65 said faces to form a sealed joint.

4. A joint for concrete conduit sections 65 comprising bell and spigot ends, and me-

tallic ring elements respectively anchored in the conduit ends, and having oppositely inclined exposed faces juxtaposed in the finished joint, together with a welded union between said faces to seal the joint.

5. A joint for concrete conduit sections comprising bell and spigot ends and metallic ring elements respectively anchored in the conduit ends and having oppositely inclined exposed faces juxtaposed in the finished joint, together with means uniting said faces to form a sealed joint, at least one of said ring elements having a portion yieldable under longitudinal strain at the joint to permit relative movement of the conduit section without rupture of the joint.

6. A joint for concrete conduit sections comprising bell and spigot ends, and metallic ring elements respectively anchored in the conduit ends, and having oppositely inclined exposed faces juxtaposed in the finished joint, together with means uniting said faces to form a sealed joint, at least one of said ring elements having a crimp therein to permit movement without rupture of the joint.

7. A joint for concrete conduit sections comprising bell and spigot ends, and metallic ring elements respectively anchored in the conduit ends, and having oppositely inclined exposed faces juxtaposed in the finished joint, together with means uniting said faces to form a sealed joint, at least one of said ring elements having a crimp therein to permit movement without rupture of the joint, and deformable packing means at said crimp.

8. A joint for concrete conduit sections comprising bell and spigot ends, and metallic ring elements respectively anchored in the conduit ends, and having oppositely inclined exposed faces juxtaposed in the finished joint, together with means uniting said faces to form a sealed joint, said rings having oppositely faced crimps to permit movement without rupture at the joint.

9. A joint for concrete conduit sections comprising bell and spigot ends, and metallic ring elements respectively anchored in the conduit ends, and having oppositely inclined exposed faces juxtaposed in the finished joint, together with means uniting said faces to form a sealed joint, said rings having oppositely faced crimps to permit movement without rupture at the joint, and deformable packing means at said crimps.

10. A joint for concrete conduit sections comprising bell and spigot ends and metallic ring elements respectively anchored in the conduit ends and having oppositely inclined exposed faces juxtaposed in the finished joint, together with means uniting said faces to form a sealed joint, at least one of said ring elements having a crimp therein to permit longitudinal displacement of the joint.

members in opposite directions without rupture of the joint, in combination with packing means to prevent leakage between adjacent joint surfaces to the metallic elements.

5. 11. A joint for concrete conduit sections comprising bell and spigot ends, and metallic ring elements of double frustro-conical shape respectively anchored in the conduit ends and having oppositely inclined exposed faces juxtaposed in the finished joint.

12. A joint for concrete conduit sections comprising bell and spigot ends, and metallic ring elements of double frustro-conical shape respectively anchored in the conduit ends and having oppositely inclined exposed faces juxtaposed in the finished joint, said exposed faces being supported by the bell and spigot flanges of the respective conduit ends.

13. A joint for concrete conduit sections comprising bell and spigot ends, and metallic ring elements of double frustro-conical shape respectively anchored in the conduit ends and having oppositely inclined exposed faces juxtaposed in the finished joint, and having a crimp in the exposed areas thereof.

14. A joint for concrete conduit sections comprising bell and spigot ends, and metallic ring elements of double frustro-conical shape respectively anchored in the conduit ends and having oppositely inclined exposed

faces juxtaposed in the finished joint, and having a crimp in the exposed areas thereof, 35 in combination with deformable packing at the crimped areas.

15. A joint for concrete conduit sections, comprising bell and spigot ends, joint-forming sheet metal rings embedded in the conduit sections at said ends, at least one of said rings being off-set to form an expansion 40 for the joint, together with reinforcing elements embedded in the conduit and in direct cooperating association with said rings.

16. A joint for concrete conduit sections, comprising bell and spigot ends, joint-forming sheet metal rings embedded in the conduit but exposed at said ends, at least one of said rings being off-set to form an expansion 50 element for the joint, together with reinforcing elements embedded in the conduit and means connecting said rings and reinforcing element directly together to insure their cooperation.

17. A joint for concrete conduit sections comprising bell and spigot ends, joint-forming sheet metal rings embedded in the conduit sections but exposed at said ends, at least one of said rings having its exposed 60 joint area supported by the bell or spigot forming flange of said conduit ends, and means for uniting said rings to seal the joint.

In testimony whereof I have signed my name to this specification.

EARL L. PETERSON.
